[57] **CLAIM**

The ornamental design for a zig-zag folding shutter, as shown and described.

DESCRIPTION

FIG. 1 is a front elevational view of a zig-zag folding shutter showing our new design;

FIG. 2 is a rear elevational view thereof;

FIG. 3 is an enlarged fragmentary cross-sectional view of the central area of a zig-zag folding shutter taken along line 3—3 of FIG. 1; and,

FIG. 4 is an enlarged perspective view of a central portion thereof.

FIG. 1

FIG. 2

FIG. 3

FIG.4
